METHOD OF MAKING PAPER FASTENERS

Edward G. Martin, Portland, Oreg., and Eugene E. Stark, Olympia, Wash.

Application June 22, 1937, Serial No. 149,674

1 Claim. (Cl. 29—13)

This invention relates generally to the stationer's art and particularly to paper fasteners.

The main object having been mentioned is a provision of an exceedingly simple and efficient form of paper fastener.

The second object is to construct a paper fastener by means of which a number of papers may be fastened together into book form and other papers may be added to the front or back thereof without removing the papers originally joined.

The further object is to construct a fastener of the type described which will lend itself to machine application.

These and other objects will become more apparent from the specification following as illustrated in the accompanying drawing in which:

Fig. 1 is a perspective view of a single fastener.

Fig. 2 is a plan showing a number of the fasteners joined.

Fig. 3 is a fragmentary section through a number of papers showing the fastener being inserted therein.

Fig. 4 is a view similar to Fig. 3 showing one end of the fastener bent over to form a head.

Fig. 5 is similar to Fig. 4 but it shows both ends bent to form heads.

Fig. 6 is a perspective view of the fastener showing one end thereof bent up for the ordinary T shaped fastener for manual insertion.

Fig. 7 is a fragmentary view showing a modified form of point.

Similar numerals refer to similar parts in the several views.

Before entering into the description of this invention, it must be understood that it is an improvement over the strip type of fasteners in which a separate head is provided, or in which the entire fastener is constructed from one piece, in that as our construction enables the user to

apply the papers to either end of the fastener instead of to one end only, as was heretofore necessary. Referring in detail to the drawing, there is shown a pair of prongs 10 having points 11 at each end thereof. The points 11 are offset as indicated as a common provision to facilitate a separation thereof.

The prongs 10 are united at an intermediate point 12 by means of spot welding or in any other convenient manner.

In the illustration, we have somewhat exaggerated

the separation between the prongs 10 which normally lie in close contact with each other.

In the drawing, the portion 12 is shown as being offset which would be the case if the material was spot welded although naturally, this would be a lesser degree.

In the form of the device in Fig. 2, the parts of fasteners 10 are united into the form of a strip by any of the well known means for temporarily uniting fasteners. The purpose of so uniting them is of course, to facilitate their use in an applicator or fastener applying machine.

It will be noted in Fig. 3 that the prongs 10 have been inserted into the opening 13 in the papers 14.

In Fig. 4 the ends 15 have been bent over to form a head on one side of the papers 14 and in Fig. 5 the ends 16 have been bent over to form a head which would be opposite the one formed by the ends 15.

It can be seen from the drawing, that additional papers 14 can be added to or removed from either side of the file without removing any of the papers from the prongs 10.

In the production of this fastener, it is desirable to assemble two sheets of metal in the manner shown in Fig. 2 and to unite them along an intermediate line by means of a continuous spot weld 12A afterward shearing into separate fasteners leaving the ends of the welded portion smooth as a result thereof. In some cases it may be found desirable to form the points 11 after the welding is performed. In such cases only the projecting end of each fastener is pointed, the other remaining blunt as shown in Fig. 7.

Obviously, the shape of the points 11 as well as the means for uniting the prongs 10 may be varied greatly without departing from the spirit of this invention.

We claim:

A method of making paper fasteners consisting of serrating the opposite edges of a pair of sheets of metal, then imposing one of said sheets upon the other in a manner that the serrations are in transverse alignment but offset from each other, then welding said sheets together along a line between and parallel with said points and then severing said joined sheets between the serrations.

EDWARD G. MARTIN. 50
EUGENE E. STARK.
